UNITED STATES PATENT OFFICE.

JAMES CARVILL GORMAN, JR., OF MANSFIELD, OHIO, ASSIGNOR TO BARNES MANUFACTURING COMPANY, OF MANSFIELD, OHIO, A CORPORATION OF OHIO.

DIAPHRAGM PUMP.

Application filed May 27, 1920. Serial No. 384,693.

To all whom it may concern:

Be it known that I, JAMES CARVILL GORMAN, Jr., a citizen of the United States, residing at Mansfield, in the county of Richland and State of Ohio, have invented certain new and useful Improvements in Diaphragm Pumps; and I do hereby declare the following to be a full, clear, and exact description of the invention, such as will enable others skilled in the art to which it appertains to make and use the same.

This invention relates to diaphragm pumps, and more particularly to diaphragm pumps of the closed type.

The objects of the invention are to provide a simple, efficient and durable pump of the character referred to which shall consist of fewer parts than are ordinarily employed in pumps of the same type as heretofore ordinarily constructed, and in which the parts are assembled in compact form, combined with a jack mounted on and forming a part of the pump structure, instead of being made separate and supported independently of the pump proper, permitting the diaphragm to be removed without removing the jack. A further object is to provide the pump with a straight water passage therethrough and diametrically opposite suction and discharge valves, so as to render less liable the clogging of the pump with solids, which may be more easily moved by the flowing column of water in a straight horizontal direction than when lifted, and to cause the water to pass under the diaphragm and thus prevent the latter from being subjected to as much abrasive action as it is in a pump of the open spout type, in which the water and the solids are brought into contact with both sides of the diaphragm, greatly increasing the wear.

The invention will first be hereinafter more particularly described, with reference to the accompanying drawings, which form a part of this specification, and then pointed out in the claims at the end of the description.

In said drawings,

Fig. 1, is a transverse sectional elevation of a diaphragm pump embodying my invention;

Fig. 2, is a plan view of the same;

Fig. 3, is a side elevation; the air chamber at the discharge end of the waterway being removed;

Fig. 4, is a plan view of the pump proper; the jack being removed; 55

Fig. 5, is a detail sectional view illustrating the means employed for attaching the diaphragm and jack to the pump body or casing;

Fig. 6, is a detail plan view of the two 60 part clamping ring showing the two sections disconnected; and

Fig. 7, is a detail edge view of a portion of the clamping ring, showing the joint between the two sections in assembled relation. 65

Referring to said drawings, in which the same reference letters are used to denote corresponding parts in different views, the letter A denotes the pump body or casing, which has a straight waterway α therethrough provided with diametrically opposite inlet and outlet or suction and discharge valves α^1 and α^2 , respectively, and a circular opening in its top; said valves being arranged in the same horizontal plane and 70 adapted to open in the same direction. These valves are each preferably seated in an inclined position on the free end of a tubular boss which extends in a horizontal direction from a disk or plate of metal B, or B^1 placed 75 between the pump body and a pipe section or coupling member C, or C^1 , one at the inlet end and the other at the discharge end of said waterway; said pipe sections C and C^1 forming extensions of said passage and having 80 exteriorly threaded outer end-ports for connecting the same with a source of supply at one side and with a discharge pipe at the other side of the pump. The coupling member C^1 , adjacent the discharge valve, 85 has an air chamber D mounted thereon in communication therewith and a clean-out opening below the plane of the discharge valve; said clean-out opening being closed by a cover-plate e. A jack E, is mounted 95 upon the pump body or casing above the opening therein and has journaled thereon a crank shaft F which is geared to a counter-shaft F^1 which carries at one end thereof pulleys f for connection with a belt driven 100 from a power engine or other driving means. Said pulleys, however, may be replaced, if desired, by a driving gear for direct connection with the engine. The crank shaft F is journaled in suitable bearings therefor on 105 the jack E and has secured thereto a pitman

rod f^1 the lower end of which is bolted or otherwise secured to a piston or plunger G, attached to a flexible diaphragm H, the outer edge or margin of which is clamped 5 between a ring I, pressing thereon, and an annular member or flange surrounding the opening in the pump casing, on which surrounding portion the edge of the diaphragm rests. The ring I is constructed in separable 10 parts of semi-cylindrical form, each having a plurality of apertured lugs thereon for securing the two parts together and to the pump casing and both adapted to be made from one pattern. To this end each part is 15 formed with diametrically opposite lugs i and i' , the lugs i on one part or half of the ring being arranged above or below the plane of the corresponding lug i' on the other half, so as to adapt one pair of lugs 20 to rest upon the other pair, as shown in Fig. 7, thereby permitting the two parts of the ring to be secured together by bolts K which serve also to secure the clamping ring to the pump body or casing. To this end said 25 bolts pass through apertured lugs a^3 on the casing A, which project laterally beyond said bolts and are provided with bolt holes near their free ends to receive fastening bolts L which also pass through apertured lugs e on 30 the lower ends of the legs of the jack E, for securing the jack to the pump casing (see Figs. 4 and 5). As shown, the lugs a^3 are so formed that the holes therein for the fastening bolts of the clamping ring are $\frac{1}{2}$ inch 35 lower than the holes which receive the anchor bolts for the jack, so as to permit of the machining of that part of the base of the pump upon which the jack and the clamping ring rest. The feet of the jack are also machined. By merely removing the four bolts 40 which hold the clamping ring in place and the two bolts by which the end of the pitman rod f^1 is fastened to the plunger, the clamping ring and plunger are loosened so 45 that they may be removed with the diaphragm without removing or changing the position of the jack and thus get it out of alinement.

I thus provide a diaphragm pump which 50 possesses many advantages over diaphragm pumps of a similar character as heretofore ordinarily constructed in that it consists of fewer parts and less material composing the pump and jack and the jack being mounted 55 directly on the pump instead of separate therefrom, the parts are assembled in more compact form, and the pump is lighter and less expensive to make, because of the fewer parts and method of assembling the same. 60 Being of the closed type, the pump may be used for handling noxious liquids, and the water may be conducted to any desired point through a flexible canvas hose, whereas with the ordinary open spout type an unwieldy 65 wooden trough is necessary. The valves be-

ing arranged diametrically opposite each other at opposite ends of a straight water way renders less liable the clogging of the pump with solids, which can be washed more easily in a straight horizontal direction than 70 they can be lifted, and as the water passes entirely under the diaphragm the latter is not subjected to as much abrasive action as it is in the open spout type where the water and the solids come in contact with both 75 sides of the diaphragm and thereby greatly increase the wear. Furthermore, in pumps of the open spout type as heretofore constructed, in which the pump operating lever or walking beam is supported on the bearing 80 rings which hold the diaphragm in place, it is necessary, in order to remove and replace the diaphragm, which has not a very long life, to practically dismantle the upper part 85 of the pump, which is a difficult job, and requires much time and labor, whereas with my improvement it is not necessary to do this, since the diaphragm is fastened to the base of the pump by a clamping ring which is made entirely separate from the jack and 90 is removable without removing the jack, and since the diaphragm is of rubber and therefore compressible, it follows that if the bolts on one side of the ordinary bearing ring are tightened more than the bolts on the other 95 side, the bearing ring will be thrown out of alinement and in replacing the diaphragm very careful and accurate adjustment is required to make sure that all the working 100 parts of the pump are in alinement, whereas in the new pump hereinbefore described, since the body of the pump jack rests upon the pump body instead of on one edge of the rubber diaphragm, there is no possibility of 105 getting the pump jack out of alinement, and if it becomes necessary to remove the pump jack it can always be replaced in the same position that it originally occupied.

Having thus described my invention what I claim as new and desire to secure 110 by Letters Patent is:

1. In a diaphragm pump, a casing having a water passage therethrough and an opening in its top, and inlet and outlet valves on opposite sides of said opening, a 115 diaphragm or plunger having a flexible circumferential portion with the outer edge thereof resting on said casing around the margin of said opening, said casing also having integral radially extending projections with off-set end-portions, means for clamping said outer edge down upon the inner portions of said projections, and a jack mounted on said casing having a crank-shaft journaled thereon and provided with 120 a pitman-rod connection with said plunger, said jack having supporting legs with their lower ends resting upon the end-portions 125 of said projections exterior to said clamping means and provided with means for 130

securing said lower ends of said legs to said end-portions of said projections, whereby said clamping means and diaphragm or plunger may be removed without removing 5 or changing the position of the jack.

2. In a diaphragm pump, a casing having a water passage therethrough and an opening in its top, and inlet and outlet valves on opposite sides of said opening, a 10 diaphragm or plunger having a flexible circumferential portion with the outer edge thereof resting on said casing around the margin of said opening, said casing also having integral radially extending projections 15 with off-set end-portions, the inner portions of said projections and the end-portions thereof being apertured, and said end portions raised above the plane of said inner portions, a clamping ring and fastening 20 bolts for pressing said outer edge down upon the inner portions of said projections, and a jack mounted on said casing having a crank-shaft journaled thereon and provided with a pitman-rod connection with 25 said plunger, said jack having supporting legs with their lower ends resting upon the end-portions of said projections exterior to said clamping ring and fastening bolts for securing said lower ends of said legs to said 30 end-portions of said projections, whereby said clamping means and diaphragm or plunger may be removed without removing or changing the position of the jack.

3. A pump casing having a water passage therethrough and an opening in its top, intake and discharge valves controlling said passage, a flexible diaphragm closing said opening and a ring with co-operating means for clamping the edge of said diaphragm 40 between it and said casing, said ring being constructed in separable parts having diametrically opposite apertured lugs thereon arranged in different horizontal planes, whereby the lugs on one part are adapted to 45 rest upon the co-operative lugs on the other part for securing them together and to the pump body or casing.

4. In a diaphragm pump, a clamping ring for securing the perimeter of the diaphragm 50 between it and a surrounding portion of an opening in the top of the pump casing closed by said diaphragm; said ring being constructed in separable substantially semi-circular parts each having substantially 55 diametrically opposite apertured lugs thereon, the lugs on one part being arranged below the plane of the lugs on the other part, so that the lugs on one part may rest upon the co-operative lugs on the other part in 60 position to receive fastening bolts for securing them together and to the pump body or casing.

5. In a diaphragm pump, a casing having a water passage therethrough and a circular 65 opening in its top, a diaphragm closing said

opening, a plunger carried by said diaphragm and means for operating said plunger, together with means for removably securing said diaphragm in place; the latter means consisting of radially projecting apertured lugs on said casing spaced apart around said opening, and a clamping ring constructed in two parts each having radially projecting apertured lugs overlying the lugs on the pump casing, and fastening bolts inserted through overlapping lugs on the two parts of said ring and through an underlying lug on said casing for securing said ring to said casing and thereby clamping the outer margin of the diaphragm between 70 said two-part ring and underlying parts of the casing. 75

6. The combination, in a diaphragm pump, of a casing having a valve-controlled water passage therethrough and an opening 80 in its top, a diaphragm closing said opening, and means for removably securing said diaphragm in place; said means consisting of a ring having radially projecting lugs 85 overlying lugs on the pump casing and fastening bolts entering holes in said lugs for securing said ring to said casing and clamping the outer margin of the diaphragm between it and the casing; said clamping ring being constructed in separable parts 90 each of semi-cylindrical form and having diametrically opposite apertured lugs thereon, the lugs on one part being arranged above the plane of the lugs on the other part and resting thereon and bolts passing through said lugs and an underlying part of the pump casing so that the same bolts are used for securing the two parts together and clamping the diaphragm between the 95 casing and said ring. 100

7. In a diaphragm pump, a casing having a water passage therethrough and an opening in its top, valves controlling said passage, a flexible diaphragm closing said opening, a plunger carried by said diaphragm 105 and adapted to project into said water passage, a jack mounted on the pump body directly over said opening and supporting the driving mechanism for imparting movement to said diaphragm and plunger, and means independent of said jack for removably clamping the edge of the diaphragm to the casing; said means consisting of a clamping ring constructed in separable parts having diametrically opposite apertured lugs 110 thereon arranged in different horizontal planes so that the lugs on one of said parts will overlap and rest upon the co-operative lugs on the other part, and fastening bolts inserted through cooperative lugs in said 115 ring and registering apertures in radially projecting lugs on said casing on which the feet of said jack rest exterior to said ring. 120

8. In a diaphragm pump, a casing having a water passage therethrough and an open- 125

ing in its top, a flexible diaphragm closing said opening, a plunger carried by said diaphragm and adapted to project into said water passage when in its lowermost position, and a jack mounted on the pump over said diaphragm and having bearings thereon in which is journaled a crank shaft having a pitman rod connecting the shaft with said diaphragm for imparting movement thereto; said jack having legs provided with radially projecting apertured lugs, radially projecting apertured lugs on the pump casing on which the lugs of the jack rest, and fastening bolts passing through 10 registering apertures in said lugs for detachably securing the jack upon the casing,

together with means for clamping the marginal portion of said diaphragm between the jack and the top of the casing around the margin of said opening, said means consisting of a clamping ring having radially projecting apertured lugs thereon and fastening bolts inserted through said lugs and through registering apertures in the lugs on the casing on which the feet of the jack rest 20 25 exterior to said ring.

In testimony whereof I affix my signature in the presence of two witnesses.

JAMES CARVILL GORMAN, JR.
